UNITED STATES PATENT OFFICE.

HENRY D. BOKOP, OF DEFIANCE, OHIO.

BOX-SECTION.

1,068,304.

Specification of Letters Patent.

Patented July 22, 1913.

Application filed August 12, 1912. Serial No. 714,665.

To all whom it may concern:

Be it known that I, HENRY D. BOKOP, a citizen of the United States, residing at Defiance, in the county of Defiance and State 5 of Ohio, have invented a new and useful Box-Section, of which the following is a specification.

The present invention relates to boxes, crates, and the like, particularly those which 10 are constructed of sections.

It is the object of the present invention to provide a novel and improved section for the construction of boxes, crates and the like, which shall embody a frame and a panel in 15 connection with a wire passing back and forth across the frame to reinforce the panel and engaged to the frame in a peculiar manner.

It is also the aim of the present invention 20 to provide such a section, which shall be of utmost simplicity, which shall be inexpensive and substantial in construction, as well as convenient, and efficient in use.

With the foregoing and other objects in 25 view which will appear as the description proceeds, the invention resides in the combination and arrangement of parts and in the details of construction hereinafter described and claimed, it being understood that 30 changes in the precise embodiment of the invention herein disclosed, can be made within the scope of what is claimed, without departing from the spirit of the invention.

The invention has been illustrated in the 35 accompanying drawings in its preferred embodiment, wherein like reference characters have been employed to denote corresponding parts, and wherein—

Figure 1 is a perspective view of a box 40 constructed of a number of sections according to the present invention, parts being broken away. Fig. 2 is a side elevation of one of the sections, with the inner ply of the panel removed. Fig. 3 is a side elevation of 45 the outside of the section. Fig. 4 is a transverse section. Fig. 5 is a sectional detail.

Referring specifically to the drawings, each of the sections comprises a rectangular frame 6 constructed of wooden strips connected at the corners in any well known manner, such as by mortise and tenon joints. This frame is provided with a series of 50 transverse kerfs or notches 7 along the outer edge of each of its sides and ends in order to provide wire engaging means around the frame.

The frame may be of any preferred construction and in adapting the frame to the present invention, it is only necessary to cut the kerfs 7 around the outer edges thereof. A wire of high tensile strength and of the smallest possible gage is then passed back and forth over the inner face of the frame 6 to provide the lateral and longitudinal strands 8 and the diagonal strands 9 at 60 the corners of the frame, the wire being looped through the respective kerfs 7 and over the other face of the frame adjacent the outer edges thereof, as indicated by the numeral 10. This wire is drawn taut when it 65 is bent back and forth between the sides and ends of the frame and the ends of the wire may be secured to the frame by means of small tacks or other securing members. It is also understood that several lengths of 70 wire may be employed instead of one single length, if desired. The wire in thus being passed back and forth across the inner face of the frame provides a network or mesh, the diagonal corner strands 9 serving to 75 brace the frame as well as coöperating with the transverse and longitudinal strands 8 to provide the meshwork.

The panel is secured as usual to the inner face of the frame, the panel being two plied, 80 one of the plies being secured to the inner face of the frame underneath the wire strands and having notches in its periphery registering with the kerfs 7, and the other 85 ply being secured to the inner face of the frame over the wire strands, so that the meshwork of wire is interposed or sandwiched between the two plies of the panel. The panel is thus reinforced and is not 90 readily broken open or pressed out of position. The wire in being engaged to the frame by means of the kerfs 7 is practically 95 invisible, the loops 10 being arranged along the outer edges of the frame so as not to encumber the frame or otherwise destroy the 100 usual appearance thereof.

In use, the box, crate or the like, is built up from a number of the sections, the sections being provided in various sizes so that 105 various sizes and forms of boxes, crates, and the like may be built up.

From the foregoing, taken in connection with the drawings, the advantages and capabilities of the present invention will be apparent, and it will be noted that the objects aimed at have been carried out in such 110 a manner that the present device provides a

desirable one for the purposes for which it is designed.

Having thus described the invention what is claimed as new is:—

5 1. A box section embodying a frame provided with a series of transverse kerfs along the outer edge of each side and end, a panel secured to one face of the frame, and a wire passed back and forth over the said face of the frame to reinforce the panel and looped through the kerfs and over the other face of the frame.

10 2. A box section comprising a rectangular frame provided with a series of transverse kerfs along the outer edges of each side and

end, a panel secured to the inner face of the frame, and a wire passed back and forth over the said face of the frame to provide longitudinal and lateral strands and diagonal strands at the corners, the wire being looped 20 through the kerfs and over the outer face of the frame and serving to reinforce the panel.

In testimony that I claim the foregoing as my own, I have hereto affixed my signature 25 in the presence of two witnesses.

HENRY D. BOKOP.
